United States Patent Office.

STEPHEN W. DOWNEY, OF PIEDMONT, WEST VIRGINIA.

Letters Patent No. 74,322, dated February 11, 1868.

IMPROVEMENT IN TRUNK-LABELS.

The Schedule referred to in these Letters Patent and making part of the same.

TO ALL WHOM IT MAY CONCERN:

Be it known that I, STEPHEN W. DOWNEY, of Piedmont, in the county of Mineral, and State of West Virginia, have invented certain new and useful Improvements in the Method of Attaching the Address to Trunks, Freight and Express-Boxes, Cans, &c., by means of a slate properly attached to the same; and I do hereby declare that the following is a full, clear, and exact description of the same, reference being had to the annexed drawings, and to the letters of reference marked thereon, making part of this specification, and in which—

Figure 1 is a plan view of a section of the top of the trunk with my device attached, and the hinged top and slide removed.

Figure 2 is the same with the top closed.

Figure 3 is a base of the frame for the slate, showing the means by which it may be attached to the trunk.

Figure 4 is a sectional view through the centre of the trunk, with my device attached.

Figure 5 is a trunk, with my device attached to the top.

Figure 6 is an end view of a trunk, showing my device.

The object of my invention consists in providing a simple and practical means by which any address that may be desired can readily be applied to a trunk, valise, box, can, or basket, and, when occasion requires, can readily be obliterated in order that the same may be changed. To accomplish this, I use an ordinary slate or like substance. I prefer slate for the purpose, owing simply to the fact that any writing that may be placed on the same can so readily be obliterated. The slate I place in a suitable frame, which is provided with projecting lips or cleats to retain the slate in suitable position. This frame may be cast with the base-plate, or, when made of wood or sheet metal, can be firmly secured thereto.

To the base or frame, I securely hinge a top, in which there is secured, by suitable means, a glass, its surface being protected by rods and a sliding top. The case thus constructed, I insert in the top or end of the trunk, valise, freight-box, or can.

The great advantage of this arrangement will readily suggest itself to all who are in any way familiar with the uses for which it is intended. Scarcely an individual can be found who has not experienced, at one time or another, great inconvenience in consequence of the failure to have at hand a suitable means whereby a desired address could be attached to the trunk or other article. Cards in the form of tags are generally used for the purpose, the same being tacked or tied to the trunk. These methods are both most objectionable. Railroad men are proverbial for the careless and rough manner in which they handle baggage, and it naturally follows that the address, when written on cards or pieces of paper and tacked or tied to the trunk, is exceedingly insecure. The same or even greater inconvenience is experienced with freight-boxes and cans, which are constantly being shipped to and fro on the cars. My improvement is especially applicable to cans that are to be used in the milk and oyster business.

To enable others skilled in the art to make and use my invention, I will proceed to describe its construction and operation.

A is an ordinary trunk. In a suitable opening cut in the top or end of the trunk, I insert the base, B, of the tablet-case. This base, B, may be provided with cleats *b b*, by which it may be secured to the trunk; or, the opening may not be cut entirely through the trunk, then the base, B, can readily be secured by means of shut-screws inserted through the holes *b' b'*. This base, B, may be made of cast iron, sheet metal, wood, or other suitable material. When made of cast iron, there is cast with it a frame, C, or when of sheet metal or wood, the frame C is firmly secured thereto by any suitable means. This frame C is provided with projecting lips or other suitable means for retaining the slate in proper position. D is a slate that is inserted in the frame. This frame C may be constructed with suitable appliances for retaining a sponge and pencil. E is a hinged top, and is so constructed that there can readily be inserted a glass, F. Across this top E there are inserted rods or wires *e*, to protect the glass. In the top, above the wires *e e*, are grooves *g g*, in which can be inserted a sliding top, G. In inserting the frame in the trunk, the opening in the latter will have to be sufficiently wide to allow a space for the edge of the top to rest in when the same is opened or thrown up, as shown in fig. 5. Over this opening I place a spring-plate, H, which is secured to the trunk, and is of width sufficient to cover the entire space, and also to have a secure bearing on the top E. This spring answers a double purpose; it not only covers the space

for the open top to rest in, but also aids in retaining the top E in proper position. I is a lock attached to the trunk, and so arranged that its bolt will enter the top E, and securely fasten the same.

Having thus fully described my invention, what I claim as new therein, and desire to secure by Letters Patent of the United States, is—

1. Inserting in the body of a trunk, box, or can, a tablet-case, when the same is provided with a slate, and the whole is constructed and arranged substantially as described.
2. The spring H, in combination with a tablet-case, when the same is constructed and arranged substantially as described.
3. The combination of the tablet-case and slate, when the former is provided with a sliding top, and the whole is constructed and arranged substantially as described.

In testimony whereof, I have signed my name to this specification in the presence of two subscribing witnesses.

STEPHEN W. DOWNEY.
